UNITED STATES PATENT OFFICE.

GEORGE J. GAUBERT, OF RICHMOND, CANADA.

MACHINE FOR FORMING HEELS OF LAMP-CHIMNEYS.

SPECIFICATION forming part of Letters Patent No. 566,514, dated August 25, 1896.

Application filed October 31, 1895. Serial No. 567,553. (No model.)

To all whom it may concern:

Be it known that I, GEORGE JAMES GAUBERT, manufacturer, of Richmond, in the county of Richmond and Province of Quebec, Canada, have invented certain new and useful Improvements in Machines for Forming the Heels of Lamp-Chimneys; and I do hereby declare that the following is a full, clear, and exact description of the same.

This invention has for its object to provide a simple and effective machine for shaping the heels or necks of lamp-chimneys generally during the process of manufacture, which act has hitherto been performed by hand and requiring the services of a skilled workman, the machine being also specially adapted for the shaping of the heels of chimneys of the construction shown in Canadian Patent No. 46,664, of July 26, 1894, to Walter E. Mayo, in which a number of air-inlets are formed at the base by means of indentations in the edge thereof.

To such ends, therefore, the invention consists in a machine in which the main feature is an expansible rotary interior spreader over which the outer end of the bulb of glass, while still soft and adhering at its opposite end to the blowpipe, is placed, the spreader being normally in a contracted position until the bulb is in place and then expanded, the spreader, nevertheless, rotating permanently; a second feature consisting in the arrangement of a series of stationary pins or projections in such position relatively to the spreader that they will coincide with the edge of the chimney-heel after having been fully acted upon by the spreader and by a subsequent pressure of the heel against them form the depressions required in the special form of chimney above mentioned, while a third

feature calls for the addition to the parts just described of an exterior rotary former acting in conjunction with the spreader to establish the thickness of the heel, as well as to properly shape the outside surface thereof, these, with other features of detail and general construction of the carrying-frame and operating parts, being hereinafter more particularly described, and pointed out in the claims.

Having thus referred to the object and

principle of my invention, I will now describe what I consider to be the most practicable embodiment thereof in an operative machine, reference being had to the annexed drawings, 55 forming a part of this specification, in which like symbols indicate corresponding parts and wherein—

Figure 1 is a side elevation of the machine; Fig. 2, a front elevation thereof; and Fig. 3, 60 a longitudinal vertical section of same, Fig. 2.

The frame of the machine as shown comprises a base-plate *a* and front and rear standards *a'* *a''*, the standards providing bearings for an upper main operating-shaft *b*, 65 which is tubular, and a lower counter-shaft *c*.

A driving-pulley *d* is carried by the main shaft *b* as well as a gear-wheel *e*, intermeshing with a pinion *c'* on the counter-shaft and through which the latter is operated.

The main shaft *b* is made tubular in order to receive a spindle *f*, which extends through and projects beyond each end of same and which has a feather-and-groove connection *f'* *f''* therewith to allow of its sliding longitudinally therein while rotated thereby.

The projecting rear end of the spindle *f* carries a pair of fixed collars *g*, between which a collar *h* with projecting pins *h'* is held loosely in position so that such pins *h'* can be 80 engaged by the slotted and forked ends *k'* of one arm of a bell-crank lever *k* fulcrumed at *k''* to the rear standard *a''*, the opposite arm being suitably connected to a treadle or other usual operating means (not shown) for reciprocating the spindle in a frontward direction, while a retractile spring *m*, having one end attached to the lever and the other to the frame, serves to move the spindle in a rearward direction and retain it normally in its 90 rearward position.

On the front projecting end of the reciprocating spindle is arranged the spreader, which consists of an expansible head, preferably made up of a central hub or carrier section *n*, having a screw-thread connection with the spindle, and a number (three being shown in this case) of centrifugally-movable fingers *n'*, preferably of bell-crank lever form, with short and long arm portions and pivotally connected at the end of the short-arm portion to the central hub-section *n* so that the

ends of their longer and forwardly-projecting arm portions will converge and be normally in contact with each other at a central point in line with the axis of the reciprocating spindle.

- 5 Thus far I have described mechanism sufficient to produce a new and useful result if centrifugal force alone were to be relied on to throw the spreader-fingers outward, but 10 I nevertheless prefer, in order to avoid running the machine at a higher speed than is necessary, to fulcrum the spreader-fingers, as at o , to lugs p projecting from the face of a disk p' rigidly secured upon the front end of 15 the main driving-shaft b , so that they will be operated positively as levers and their longer arms moved centrifugally by the forward movement of the reciprocating spindle acting through the hub upon the shorter arms.
- 20 In order to make the indentations in the edge of the heel as called for in the special construction of chimney before mentioned, a stationary ring or face-plate q is situated in advance of the disk p' (being preferably 25 formed in one with the front standard through integral connecting-arms q') and having removably secured to its face by screws r' a ring r with any desired number of pin projections r^2 on its face in such a position as to 30 be in line with the edge of the chimney-heel when spread to its full diameter.

The outer peripheral edge of the ring r projects sufficiently beyond the edge of the stationary face-plate q to provide a journal-bearing for the outer or exterior rotary former or "fitter" for securing a uniformity of 35 outside or peripheral diameters among the lamp-chimney heels of any particular size, and such outer former or fitter is preferably 40 constructed as follows:

An annular section or ring s , having a flange s' projecting frontwardly from its inner peripheral edge and gear-teeth s^2 cut in its outer peripheral edge, is formed with a recess s^3 in 45 its rear face to fit over the journal-bearing formed by the edge of the ring r and is held in place, so as to be rotatable thereon, by means of a retaining-ring t , secured by screws t' to the rear face of the annular section s 50 and having its inner edge overlapping the rear face of the journal-bearing or ring r .

The outer former is rotated in an opposite direction to that of the inner spreader through a pinion u on the counter-shaft c , intermeshing 55 with a second pinion u' , carried on a stub-axle u^2 , mounted in the front standard, which in turn intermeshes with the gear-teeth of the annular section s of such former.

In explanation of the operation of the machine it may be stated that both the interior spreader and the outer former are permanently rotating in opposite directions, but with the spreader normally in its contracted position, and after the glass bulb has been 60 blown to the required size and its outer end sheared off such outer end is introduced be-

tween the spreader and former and the spreader expanded by throwing the sliding spindle forward, and when the heel is formed the bulb is pressed farther inward, so 70 that the pins or projections r^2 can make the required indentations in the edge thereof if the chimney is to be of the special form before mentioned.

To secure accuracy in introducing the bulb 75 between the spreader and former so as to be truly concentric with the spreader, I prefer to use the guides or rests v , (indicated by dotted lines in Figs. 1 and 2,) in which the blowpipe with bulb attached can be placed, such guides 80 being in proper position to secure the exact alinement of the blowpipe and spindle.

In order to provide for the forming of heels of different diameters, the interior spreader, the ring with the projections, and outer former 85 are readily removable and interchangeable with others of various sizes.

What I claim is as follows—

1. A chimney-heel-forming machine having an expansible rotary spreader for acting 90 interiorly upon the glass of the bulb forming the heel, with means for forming indentations in the edge of such heel and for supporting and operating such spreader.

2. In a chimney-heel-forming machine, the 95 combination of a frame, a rotating shaft, a reciprocal spindle carried by and rotating with such shaft, a number of centrifugally-movable spreader-fingers pivotally connected with such spindle, one or more pin projections 100 from such frame and means for reciprocating such spindle, for the purpose set forth.

3. In a chimney-heel-forming machine, the combination of a frame, an expansible rotary spreader formed of a number of centrifugally-movable fingers normally converging to a central point, one or more pin projections 105 from such frame and means for carrying such fingers, means for retaining them in their normal position, and means for rotating the 110 spreader for the purpose set forth.

4. A chimney-heel-forming machine having an expansible rotary spreader for acting interiorly, and an outer rotary former for acting exteriorly, upon the glass of the bulb 115 forming the heel, said spreader and former rotating independently of each other and means for supporting and operating such spreader and former, for the purpose set forth.

5. In a chimney-heel-forming machine, the 120 combination of a frame, a rotating shaft, a reciprocal spindle carried by and having an operating connection with such shaft, a number of centrifugally-movable spreader-fingers pivotally connected with such spindle, an 125 outer former rotatable independently of said spindle and carried by such frame, and means for reciprocating said spindle, and means for rotating such outer former independently of said spindle and means for rotating said 130 shaft, for the purpose set forth.

6. A chimney-heel-forming machine, the

combination of a frame, bearings carried by said frame, a main shaft and a counter-shaft mounted in said bearings, an expansible rotary spreader carried by said main shaft, a 5 rotary former carried by said frame and encircling such spreader and means for rotating said spreader and former, for the purpose set forth.

7. A chimney-heel-forming machine, the 10 combination of a frame, bearings carried by said frame, a main shaft and a counter-shaft mounted in said bearings, an expansible rotary spreader formed of a number of centrifugally-movable fingers carried by said 15 main shaft a rotary former carried by said frame and encircling such spreader and means for rotating said spreader and former, for the purpose set forth.

8. In a chimney-heel-forming machine, the 20 combination of a frame, an expansible rotary spreader formed of a number of centrifugally-movable fingers, normally converging to a central point, one or more pin projections from such frame, a rotary outer former carried by such frame, and means for carrying such fingers, means for retaining them in their normal position, and means for rotating the spreader and outer former, for the purpose set forth.

30 9. A chimney-heel-forming machine having an expansible rotary spreader for acting interiorly, and an outer former for acting exteriorly upon the glass of the bulb forming the heel, with means for forming indentations 35 in the edge of such heel, and for supporting and operating such spreader.

10. In a chimney-heel-forming machine, the 40 combination of a frame, a rotating shaft, a reciprocal spindle carried by and rotating with such shaft, a number of centrifugally-movable spreader-fingers pivotally connected with such spindle, an outer rotary former carried by such frame, one or more pin projections from such frame, and means for reciprocating such spindle, and for rotating such outer former, for the purpose set forth.

11. In a chimney-heel-forming machine, the 45 combination of a frame bearings carried by said frame, a tubular main shaft and a counter-shaft mounted in said bearings, a reciprocating spindle carried within such tubular main shaft, and having a feather-and-groove connection therewith, an expansible rotary spreader formed of a number of movable 50 fingers carried by a hub-section mounted on the forward end of such spindle, a rotary former carried by such frame, means for rotating such spreader and outer former, and means for reciprocating said spindle, for the purpose set forth.

12. In a chimney-heel-forming machine, the 55 combination of a frame, bearings formed upon said frame, a tubular main shaft and a counter-shaft located below such main shaft, said 60 shaft being a reciprocating spindle carried within such tubular main shaft, and having

a feather-and-groove connection therewith, an expansible rotary spreader formed of a number of movable fingers carried by a hub-section mounted on the forward end of such 70 spindle, a rotary former carried by such frame, means for rotating such spreader and outer former, and means for reciprocating said spindle, for the purpose set forth.

13. In a chimney-heel-forming machine, the 75 combination of a frame, bearings formed upon said frame, a tubular main shaft and a counter-shaft mounted in said bearings, a reciprocating spindle carried within such tubular main shaft projecting beyond each end of 80 same, and having a feather-and-groove connection therewith, a pair of fixed collars carried by the rear end of such spindle, a bell-crank lever fulcrumed to the rear standard and having one arm forked and engaging a 85 loose collar between such collars, the other arm being connected to a treadle, an expansible rotary spreader formed of a number of movable fingers carried by a hub-section 90 mounted on the forward end of such spindle, a rotary former carried by such frame, and means for rotating such spreader and outer former, for the purpose set forth.

14. In a chimney-heel-forming machine, the 95 combination of a frame, bearings formed upon said frame, a tubular main shaft and a counter-shaft mounted in said bearings, a reciprocating spindle carried within such tubular main shaft and having a feather-and-groove 100 connection therewith, an expansible rotary 105 spreader formed of a number of centrifugally-movable fingers carried by a hub-section mounted on the forward end of such spindle, a rotary former, carried by such frame, and means for rotating such spreader and former, and means for reciprocating said spindle for the purpose set forth.

15. In a chimney-heel-forming machine, the 110 combination of a frame, bearings formed upon said frame, a tubular main shaft and a counter-shaft mounted in said bearings, a reciprocating spindle carried within such tubular main shaft and having a feather-and-groove 115 connection therewith, an expansible rotary spreader formed of a number of movable fingers carried by a hub-section mounted on the forward end of such spindle, one or more pin 120 projections carried by the frame, a rotary former carried by such frame, and means for rotating such spreader and outer former, and means for reciprocating said spindle, for the purpose set forth.

16. In a chimney-heel-forming machine, the 125 combination of a frame bearings formed upon said frame, a tubular main shaft and a counter-shaft mounted in said bearings, a reciprocating spindle carried within such tubular main shaft, and having a feather-and-groove 130 connection therewith, an expansible rotary spreader formed of a number of movable fingers carried by a hub-section mounted on the forward end of such spindle, a rotary

former consisting of an annular section or ring rotatably carried by such frame and encircling such spreader, and means for rotating such spreader and outer former, and means for reciprocating said spindle for the purpose set forth.

17. In a chimney-heel-forming machine, the combination of a frame bearings formed upon said frame, a tubular main shaft and a counter-shaft mounted in said bearings, a reciprocating spindle carried within such tubular main shaft and having a feather-and-groove connection therewith, an expansible rotary spreader formed of a number of movable fingers carried by a hub-section mounted on the forward end of such spindle, one or more pin projections carried by the frame, a rotary former consisting of an annular section or ring rotatably carried by such frame and encircling such spreader, means for rotating such spreader and outer former, and means for reciprocating said spindle for the purpose set forth.

18. In a chimney-heel-forming machine, the combination of a frame comprising a base-plate and front and rear standards, bearings formed upon such standards a tubular main shaft and a counter-shaft located below such main shaft, such shafts being mounted in said bearings, a reciprocating spindle carried within such tubular main shaft, projecting beyond each end of same and having a feather-and-groove connection therewith, a pair of fixed collars carried by the rear end of such spindle, a bell-crank lever fulcrumed to the rear standard and having one arm forked and engaging a loose collar carried between such collars, the other arm being connected to a treadle, an expansible rotary spreader formed of a number of movable fingers carried by a hub-section mounted on the forward end of such spindle, a rotary former carried by such frame, and means for rotating such spreader and outer former, for the purpose set forth.

19. In a chimney-heel-forming machine, the combination of a frame comprising a base-plate and front and rear standards, bearings formed upon such standards a tubular main shaft and a counter-shaft located below such main shaft, such shafts being mounted in said bearings, a reciprocating spindle carried within such tubular main shaft, projecting beyond each end of same and having a feather-and-groove connection therewith, a pair of fixed collars carried by the rear end of such spindle, a bell-crank lever fulcrumed to the rear standard and having one arm forked and engaging a loose collar between such collars, the other arm being connected to a treadle, an expansible rotary spreader formed of a number of centrifugally-movable fingers carried by a hub-section mounted on the forward end of such spindle, a rotary former carried by such frame, and encircling

such spreader, and means for rotating such spreader and outer former, for the purpose set forth.

20. In a chimney-heel-forming machine, the combination of a frame comprising a base-plate and front and rear standards bearings formed upon such standards, a tubular main shaft and a counter-shaft located below such main shaft, such shafts being mounted in such bearings, a reciprocating spindle carried within such tubular main shaft, projecting beyond each end of same and having a feather-and-groove connection therewith, a pair of fixed collars carried by the rear end of such spindle, a bell-crank lever fulcrumed to the rear standard and having one arm forked and engaging a loose collar carried between such collars, the other arm being connected to a treadle, an expansible rotary spreader formed of a number of centrifugally-movable fingers carried by a hub-section mounted on the forward end of such spindle, one or more pin projections carried by the frame, a rotary former carried by such frame and means for rotating such spreader and outer former, for the purpose set forth.

21. In a chimney-heel-forming machine, the combination of a frame comprising a base-plate and front and rear standards, bearings formed upon such standards for a tubular main shaft and a counter-shaft located below such main shaft, such shafts being mounted in such bearings, a reciprocating spindle carried within such tubular main shaft, projecting beyond each end of same and having a feather-and-groove connection therewith, a pair of fixed collars carried by the rear end of such spindle, a bell-crank lever fulcrumed to the rear standard and having one arm forked and engaging a loose collar between such collars, the other arm being connected to a treadle, an expansible rotary spreader formed of a number of centrifugally-movable fingers carried by a hub-section mounted on the forward end of such spindle, a rotary former consisting of an annular section or ring rotatably carried by such frame and encircling such spreader, and means for rotating such spreader and outer former, for the purpose set forth.

22. In a chimney-heel-forming machine, the combination of a frame comprising a base-plate and front and rear standards, bearings formed upon such standards for a tubular main shaft and a counter-shaft located below such main shaft, such shafts being mounted in such bearings, a spindle carried within such tubular main shaft, projecting beyond each end of same and having a feather-and-groove connection therewith, a pair of fixed collars carried by the rear end of such spindle, a bell-crank lever fulcrumed to the rear standard and having one arm forked and engaging a loose collar between such collars, the other

arm being connected to a treadle, an expandible rotary spreader formed of a number of centrifugally-movable fingers carried by a hub-section mounted on the forward end of such spindle, one or more pin projections carried by the frame, a rotary former consisting of an annular section or ring rotatably carried by such frame and encircling such spreader,

and means for rotating such spreader and outer former, for the purpose set forth.
